UNITED STATES PATENT OFFICE.

FREDERICK H. BEROLD, OF WYOMING, OHIO.

SHEET-DELIVERY MECHANISM.

1,272,362.

Specification of Letters Patent. Patented July 16, 1918.

Application filed November 28, 1913. Serial No. 803,561.

To all whom it may concern:

Be it known that I, FREDERICK H. BEROLD, a citizen of the United States, residing at Wyoming, in the county of Hamilton and 5 State of Ohio, have invented certain new and useful Improvements in Sheet-Delivery Mechanism, of which the following is a specification.

My invention relates to sheet delivery 10 mechanism adapted for employment in machinery operating on sheets, such as printing machinery, ruling machinery, and the like. I have illustrated the same in connection with a printing machine, and shall 15 describe it in connection with such employment.

Objects of my invention are to provide 20 novel transferring mechanism for the sheets, to provide a novel sheet-receiving device, and to provide novel means for directing the sheets from the transferring mechanism to the sheet-receiving device; further to provide an impression cylinder and a sheet-receiving device thereunder, and a rotary sheet transfer located 25 in a horizontal plane between said impression cylinder and sheet-receiving device; further to arrange the parts in such manner that the sheets are delivered to the 30 sheet-receiving device printed or wet side up, the sheet-receiving device being movable from under the sheet for dropping the sheet.

It is the object of my invention further, 35 to provide novel means for causing release of the sheets from the transfer; further to provide novel means in connection with the transfer for aiding in ready delivery of the sheets; further to provide novel delivery mechanism comprising flexible carrying means movable in the direction of movement of the sheet for receiving the sheet and arranged to be retracted from under the sheet with a peeling movement; 40 further to provide novel delivery mechanism comprising a carriage and flexible carrying means bodily movable under a rotary transfer in the direction of the movement of the sheet received thereby and arranged to 45 be retracted from under the sheet by a movement of the carriage relative to the flexible carrying means; and the invention will be further readily understood from the following description and claims, and from 50 the drawings, in which latter:

Figure 1 is a side elevation of so much

of a printing machine as is necessary to illustrate my invention employed in connection therewith.

Fig. 2 is a vertical longitudinal section 60 of my improved device shown in connection with so much of a printing machine as is advisable to illustrate its connection therewith, the section being taken on a line corresponding to the line 2—2 of Fig. 3. 65

Fig. 3 is a plan view of my improved device, partly in section on a line corresponding to the line 3—3 of Fig. 2.

Fig. 4 is a vertical longitudinal section, 70 taken on the line 4—4 of Fig. 3, showing the rotary transfer and its adjacent parts.

Fig. 5 is a detail of the rotary transfer in cross-section on the line 5—5 of Fig. 3.

Fig. 5^a is a detail of the same.

Fig. 6 is a cross-section of the rotary 75 transfer on the line 6—6 of Fig. 5.

Fig. 7 is a vertical longitudinal section of the flexible carrier mechanism, taken on the line 7—7 of Fig. 3.

Fig. 8 is a cross-sectional detail of the 80 same, taken on a line corresponding to the line 8—8 of Fig. 7.

Fig. 9 is a cross-sectional detail of the same taken on a line corresponding to the 85 line 9—9 of Fig. 7.

Fig. 10 is a cross-sectional detail of the same taken on a line corresponding to the line 10—10 of Fig. 7.

Fig. 11 is a horizontal cross-sectional detail of the same taken on the line 11—11 90 of Fig. 8.

Fig. 12 is a detail in cross-section of the means for causing relative movement between the carriage and the flexible carriers or tapes, taken on a line corresponding to 95 the line 12—12 of Fig. 13.

Fig. 13 is a cross-section of the same taken on the line 13—13 of Fig. 4.

Fig. 14 is a detail in cross-section on the line 14—14 of Fig. 1, showing the means 100 for adjusting the relation of the sheet-receiving mechanism to the transfer.

Fig. 15 is a detail in section on the line 15—15 of Fig. 3 showing a side elevation of one of the draw-rolls on the transfer-shaft. 105

Fig. 16 is a rear end elevation of the carriage and its connections, partly broken away; and,

Fig. 17 is a detail of the buffer for the 110 tape-carriage taken on the line 17—17 of Fig. 16.

21 represents the main frame of the machine in which my invention is employed, illustrated as a printing machine, comprising a cylinder 22, shown as an impression cylinder, which coöperates with a type or plate cylinder 23, hereinafter designated a plate-cylinder, accomplished in ordinary or well-known manner, suitable inking mechanism being provided for the cylinder 23, not shown because well known.

10 The cylinder 22 is secured to a shaft 24 which rotates in suitable bearings in the main frame, and has a gear 25 thereon (see Fig. 1), which is meshed by a pinion 26 on a 15 drive-shaft 27, journaled in suitable bearings in the main frame and having connection with suitable driving mechanism, instanced as a drive pulley 29 fast thereon.

The cylinder 22 has a suitable number of 20 grippers 30 thereon and moving therewith, arranged to coöperate with the edge of the impression surface of said cylinder for receiving the sheet from a suitable feed-board 32, (see Fig. 2), this being accomplished 25 in any ordinary or well-known manner, the operation of the grippers for gripping the sheet and for releasing the same being accomplished in any ordinary or well-known manner, not shown because well known.

30 36 is a transerrer, shown as comprising a series of sheaves 37 on a shaft 38 journaled in bearings 39 in the main frame. (See Figs. 2 and 3.)

40, 40, are a series of sheaves on a shaft 41 35 secured in bearings 42 of the main frame. (See Figs. 2, 3 and 16).

The sheaves 37, 40, are arranged to receive 40 endless cords 43 thereover, which act to insure release of the sheets from the trans- 45 ferrer. These sheaves are arranged to be adjusted lengthwise of their respective shafts for placing the sheaves and their cords at suitable points crosswise of the sheet of paper being printed or otherwise operated on.

45 The lateral positioning of the sheaves 37 is accomplished by providing each sheave with a set-screw 44, received against a key 45 in the sheave slidable lengthwise of a groove 46 extending substantially the length 50 of the shaft 38. (See Fig. 5). The lateral positioning of the sheaves 40 is accomplished by means of collars 48 and set-screws 49, one of the collars being at each side of the sheave. (See Figs. 2 and 3). The cords 55 are received in grooves 50 in the sheaves 37 and grooves 51 in the sheaves 40.

The grooves 50 for the sheaves 37 are shown as formed in the peripheries of disks 53, (see Figs. 2, 5, 5^a and 6), releasably secured to spiders 54, as by making said disks of ring form and pluri-part and providing their inner edges with slots 55 through which bolts 56 are received and threaded into the spiders for clamping said disk-parts 60 to said spiders, the inner edges of the disk-

parts being received against lugs 57 on the spiders for positioning the same. The disks are shown as formed in halves, the slots 55 in each of the halves being parallel so that the disk-parts may be slipped over the bolts 70 and under the heads of the bolts in directions at right angles to the axis of the shaft and permitting release or attachment thereof by slight turning of the bolts.

The walls of the grooves 50 are preferably 75 formed serrated at their peripheral edges, as shown at 52, so that contact between the supporting faces of the sheaves 37 and the sheet being delivered may be reduced to the minimum and for providing contact points 80 with the sheet for removing contact of the cords from the sheet.

The shaft 38 further has draw-rolls 58 thereon, (see Figs. 3 and 16), adjustably secured lengthwise thereof in manner similar 85 to the sheaves 37. Each of these draw-rolls preferably comprises a spider 54 to which pluri-part draw-roll disks 59 are secured in manner similar to the disks 53, each of the draw-roll disk-parts being provided with parallel slots 60 at their inner edges in which the bolts 56 are received. The draw-roll disks and the sheave-disks are interchangeable on the spiders.

These draw-rolls are arranged for having 95 the sheet received over their peripheries and coat with draw-rolls 61. The draw-rolls 61 are mounted on a shaft 62 and adjustably positioned lengthwise thereof, as by means of set-screw 63. The peripheral edges of the draw-rolls are preferably cylindrical, and the mating draw-rolls are relatively so placed as to be separated just sufficient to receive the sheet of paper between them for causing contact of the draw-rolls with the 100 sheets. This contact is usually at a point 105 crosswise of the sheet which is free of printing.

The draw-roll shaft 62 is journaled in 110 bearings 65 in one end of levers 66, pivoted on a cross-shaft 67 located in bearings 68 in the main frame. (See Figs. 2, 3 and 4). The other end of each of said levers is contacted by a set-bolt 69 threaded in a lug 70 of the frame for definitely positioning the 115 recession of said draw-rolls 61 from the draw-rolls 58, a spring 71 positioning the lever toward said set-screw and thereby insuring smoothness of operation and avoiding rattling and chattering of the parts. The 120 set-bolt may be locked in position by a lock-nut 72.

75 is a gear fast on the shaft 38 and meshes with a pinion 76 on the draw-roll shaft 62 for rotating the draw-rolls 61, (see Figs. 3 125 and 4), the pitch diameters of the gear and pinion being preferably such that the peripheries of the mating draw-rolls have similar speed.

Grippers 81, 81, are provided for the 130

transferrer, (see Figs. 4, 5 and 5^a), one of said grippers preferably coacting with each of the sheaves 37 and draw-rolls 58. These grippers are adjustably secured to a gripper-shaft 82, rocking in bearings 83 in the spiders, the grippers being adjustably secured to the gripper-shaft by means of set-screws 84.

85, 86, are bearers for the transferrer which coöperate with similar bearers 87 on the impression cylinder. The bearer 85 is shown as a housing which contains gripper-operating mechanism. The bearer 85 has a bearing 88 for the gripper-shaft 82, and the gripper-shaft has a segment-gear 89 secured thereto which coöperates with the segment gear 90 of a segment arm 91 pivoted on a pin 92 secured to the bearer 85. The arm 91 has a roller 93 thereon which coöperates with a cam 94 suitably secured to the main frame. The gripper-shaft has an arm 96 secured thereto to which a rod 97 is pivoted, the rod being slideable lengthwise in a pivoted bearing 98, a spring 99 between said bearing and a shoulder 100 on said rod tending normally to close said grippers against the coacting gripping face of said transferrer. A stop 101 is provided for the gripper device.

30 The coacting gripping faces on the transferrer are preferably formed by lugs 102 on the spiders 54, the sheet-contacting faces of said lugs preferably being located at or outside the circle of the contact points of the serrated edges of the sheaves, so as to avoid impressing the sheet with said contact points by the grippers.

40 A sheet-receiving device coacts with the transferrer. This may be of suitable form for the purpose stated, and I have shown the same as consisting of flexible carrier mechanism having novel construction and properties, which will now be described.

45 106, 106, are a series of flexible carriers, instanced as tapes, which are arranged to be adjustably placed crosswise of the machine, depending on the points, for instance, of the printed surface, at which it is most desirable to locate the tapes. (See Figs. 2, 3, 7 and 50 16). These tapes are shown as endless tapes and are received about pulleys 107, 108. The pulleys 107 are shown as elongated pulleys on a shaft 109 journaled in bearings 110 in a carriage 111. The pulleys 108 are on a 55 shaft 112 in bearings 113 on said carriage.

The carriage is a reciprocating carriage. I have shown the same as comprising side frames, each of which comprises a yoke 114 and an angle-bar 115, secured thereto by 60 bolts 116. (See Figs. 2, 3, 7 and 8). The side frames are connected by a cross-shaft 117 pinned to the yokes by pins 118 and for additional rigidity the shaft 112 may be rigidly secured in the bearings 113, as by 65 set-screws 119.

As stated, the tapes are laterally adjustable, which I prefer to accomplish by means which permit lateral positioning of the pulleys 108, as by locating said pulleys between collars 121 adjustably secured to said shaft 70 112 by means of set-screws 122. The pulleys 108 upon being adjusted will properly track the tapes about the pulleys 107 so that the tapes will extend in parallel directions parallel to the direction of movement of the 75 sheet being fed. The tapes are preferably sufficiently stretched about the pulleys to cause them to move in unison and to cause them to retain their relative positions upon movement of the carriage with relation to 80 said tapes.

The carriage is arranged to travel back and forth with relation to the transferrer for receiving the sheets upon the tapes, and relative movement is caused between the carriage and the tapes for causing a recession of the tapes from under the sheet with a motion which may be called a peeling-off motion, whereby a proper dropping of the sheet may be attained.

90 By the means illustrated in the drawings, a reciprocating motion of the carriage is attained in such manner that movement of the upper stretches of the tapes will take place only in one direction.

95 Means are therefore provided whereby the upper stretches of the tapes move intermittently in one direction and the lower stretches of the tapes reciprocate.

The carriage is reciprocated in novel manner which will now be described.

100 126, 126, and 127, 127, are two pairs of sprocket-wheels. (See Figs. 1, 2, 3, 7 to 10, and 16.) Sprocket-chains 128 are received about said sprocket-wheels. The 105 sprocket-wheels 126 are fast on stud shafts 129 journaled in bearings 130 of the sides of the main frame. Pinions 131 are fast on the shafts 129 and are meshed by gears 132 fast on a cross-shaft 133, journaled in 110 bearings 134 of the main frame. A gear 135 meshes with one of the gears 132 and is journaled on a stud-shaft 136 fast in a bearing 137 in the side frame. The gear 135 may be made removable for timing 115 the travel of the carriage to the time of delivery by the transferrer, so that the sheet may be delivered by the transferrer upon selective parts of the carriage, primarily for insuring delivering of the front 120 edge of the sheet at the front end of the carriage. The removal of the gear 135 is accomplished by releasing the bolt 138 having threaded connection with the stud for securing a washer 139 in place against the 125 end of said stud for holding said gear in place. (See also Fig. 14.)

141 is a gear which is journaled on a stud 142 secured in a bearing 143 in the main frame and is meshed by a gear 144 fast 130

on the shaft 38 of the transferrer. The driving of the tape-mechanism is shown accomplished through the medium of the transferrer for the purpose of insuring proper timed movement between the trans- 5 ferrer and the tape-mechanism.

The sprocket-wheels 127 are secured to stud-shafts 146 which rotate in slide-bearings 147 adjustable toward and from the 10 bearings 130 for providing means for adjustably stretching the respective sprocket-chains or taking up slack in the same.

These slide-bearings are adjusted by 15 means of set-bolts 148 received through threaded holes in the wall of the guideway 149, jam-nuts 150 securing the set-bolts in adjusted position, the bearings being secured in adjusted positions by means of clamp-bolts 151.

20 The upper and lower stretches of the sprocket-chain are respectively supported on guides 156, 157.

The carriage is supported on rollers 161, 162, traveling between tracks 163, 164, at 25 the respective sides of the machine. Each of the side frames of the carriage is provided with a set of these rollers, which are shown journaled on axles 165, 166, secured in the yokes 114.

30 The upright guide 167 is secured to the side frame of the carriage, across the stretches of the sprocket-chain, one of these upright guide-ways being shown secured to each side frame in the present exemplification.

35 The sprocket-chains coact with these guides for causing travel of the carriage. Each of the guides is shown as provided with a channel 168 in which a roller 169 on a pin 170 on the sprocket-chain is received.

40 These connections with the carriage at both sides of the same, are preferably located in the same positions with relation to the sprocket-chain for causing ease of travel of the carriage. The guides are shown connected with the side yokes by means of 45 screws 171.

In the present exemplification, the sprocket-wheels 126 have continuous rotary motion imparted thereto for moving the sprocket-chains continuously, the stretches of the sprocket-chain in the present exemplification moving in the directions indicated by the arrows *a* and *b* respectively. (See Fig. 7.)

50 As the sprocket-chain moves, the pin 170, which forms an actuator for the sheet-receiving device, is carried with it in its movement. During travel of this pin with either stretch of the sprocket-chain, the carriage is moved in the direction in which 55 the stretch of the sprocket-chain containing the same moves. Thus when the pin moves in the direction of the arrow *a* with the upper stretch of the chain, a movement of the carriage in a similar direction is caused at 60 the speed coincident with the speed of move- 65

ment of said stretch of said chain. When the pin arrives at a point in the vertical plane of the axis of rotation of the sprocket-wheel 126, it begins to move about the outer periphery of said sprocket-wheel, thereby 70 moving in the arc of a circle and bringing the carriage to a gradual stop and again starting the carriage with an easy motion as the pin descends beyond the horizontal plane of the axis of rotation of the sprocket-wheel, this speed accelerating until the pin is in the vertical plane of the axis of rotation of the sprocket-wheel 126, when the pin again moves forward at its limit of speed, carrying the carriage with it at such speed 80 until the pin arrives at the opposite sprocket-wheel 127, when a similar reversal of movement of the carriage takes place, with a gradually decreasing and then gradually accelerating speed. The limits of re- 85 ciprocating motion of the carriage are determined by said pin and its coöperating parts.

Buffer means may, if it is desired, be provided for the tape-carriage. I have shown a buffer for each corner of the tape-carriage, instanced as comprising a piston 173 secured at each corner of the tape-carriage arranged to be received in a cylinder 174 secured to a rigid part of the machine, 90 as to the frame, this cylinder being provided with a suitable valve 175. (See Figs. 2, 3, 7, 16 and 17).

When the pin 170 is in the lower stretch of the sprocket-chain, the carriage is moving in the direction of the arrow *b*, carrying the tapes with it without relative movement between the carriage and tapes for receiving the sheet from the transferrer.

For aiding in release of the sheet from the transferrer I have provided the cord-mechanism, and for further influencing the movement of the forward edge of the sheet toward the tape mechanism I provide the cord-mechanism with directing rollers 176, 110 there being preferably a directing roller for each of the cords 43. These directing rollers are mounted on studs 177 in brackets 178 placed adjustably crosswise of the machine as on a cross-bar 179 to which they 115 are adjustably secured by set-screws 180, the cross-bar being rigidly secured to the main frame.

The forward edge of the paper being fed about the transferrer is received between 120 the coacting draw-rolls 58, 61, and the grippers of the transferrer are so timed that they will release the forward edge of the sheet when the sheet has been received between said coacting draw-rolls. The further action of the coacting draw-rolls is to cause a feeding of this forward edge of the sheet in a direction intermediate between the peripheries of the coacting draw-rolls.

The sheet is carried forward with the de- 125

livery motion of the upper stretches of the tapes.

When the front edge of the sheet has arrived at its forward limit of movement, a 5 retrograde movement of the carriage takes place, the tapes however being held, so that retrograde movement of the upper stretches of the tapes is prevented, which I accomplish by holding one or more of the tapes, 10 (see Figs. 2, 3, 4, 12 and 13), shown in the present exemplification as accomplished by jaws 186, which swing loosely about the cross-shaft 67 and coact with opposing jaws 187, shown as brackets extending from the 15 main frame. I show one of these sets of jaws coöperating with the outer tape at each side of the machine, the tapes so acted on coöperating with the pulleys 107 for arresting all the tapes.

20 Teeth 188 are shown on the jaws 186. The pivotal points of the jaws 186 are shown as in a position in rear of the contact-part of the jaws with the tape, whereby the jaws are relieved from holding action upon the 25 tapes during the feeding movement of the tapes, but act to grasp the upper stretches of the tapes to prevent retrograde movement thereof upon retrograde movement of the carriage. The effect of the holding of 30 the tapes upon retrograde movement of the carriage is to cause a relative movement between the carriage and the tapes, which acts to curl the delivery end of the tapes under the carriage and to retract the tapes from 35 the sheet with a curling motion, the support of the sheet by the tapes being removed progressively from the delivery end of the sheet toward the rear end of the sheet. This motion is accomplished quickly, and upon 40 removal of the support, the sheet drops into the receptacle 189. This receptacle may be any suitable device well known in the art for the purpose and comprises side walls, some of which are given a jogging motion 45 in well known manner to stack the sheets.

The forward limit of movement of the front edge of the sheet may be gaged by a stop or stops 181, shown adjustable cross-wise of the machine on a rod 182 secured to 50 the main frame, and adjustably positioned by set-screws 183. As the forward edge of the sheet approaches the stops, the pins on the sprocket-chains arrive in a vertical plane coincident with the vertical plane of the 55 axes of rotation of the sprocket-wheel 127, when the pins begin their travel about said sprocket-wheels and cause retardation of the speed of movement of the sheet, so that it may finally contact said stops without a 60 buckling or crushing effect upon the edge of the sheet, thereby maintaining said edge as a true edge so as to insure perfect registry of the sheet in subsequent printing or other operations.

65 My improved device provides means

whereby release of the tapes from the sheet takes place with a peeling movement, avoiding abrasive movement between the tapes and the surface of the sheet, and preventing buckling of the sheet, and provides means 70 whereby the support under the sheet is removed without disturbing the position of the sheet, but permitting the sheet to slowly settle upon the stack under the influence of its own weight. 75

Having thus fully described my invention, what I claim as new and desire to secure by Letters Patent, is:

1. A sheet delivery mechanism comprising in combination, a moving sheet transfer 80 device, a moving sheet-receiving device, and an endless cord mechanism having diagonally arranged stretches acting on the moving sheet between said moving sheet transfer device and said moving sheet for directing said moving sheet toward said receiving device. 85

2. In sheet delivery mechanism of the character described, the combination of a rotary transferrer comprising a delivery 90 sheave having a peripheral groove the walls whereof are provided with peripheral serrations the peripheral ends of which are arranged to contact the sheet and a delivery cord received in said groove. 95

3. In sheet delivery mechanism of the character described, a rotary sheet transferrer comprising a delivery sheave which comprises a supporting part and a pluri-part disk, and means for releasably securing said parts of said disk to said supporting part, the parts of said disk provided with a peripheral groove the walls whereof are formed with peripheral serrations, and a delivery cord received in said groove. 100

4. In a sheet delivery mechanism of the character described, the combination of a rotary transferrer, a reciprocating sheet-receiving device, said rotary transferrer comprising sheaves, coacting sheaves therefor, endless cords received in a pair of stretches about said sheaves and coacting sheaves, and pulleys coacting with one of the stretches of said endless cords for directing the same obliquely to a point above said sheet-receiving device. 110

5. In a sheet delivery mechanism of the character described, a rotary sheet transferrer comprising a cord-receiving sheave provided with a peripheral groove the walls 120 whereof are formed with peripheral serrations, and a gripper, said sheave provided with a peripheral coacting surface for said gripper, and said peripheral coacting surface being coincident with the longitudinal 125 projection of the peripheral edges of said peripheral serrations.

6. In sheet delivery mechanism of the character described, a rotary sheet transferrer comprising a shaft, a series of spiders 130

adjustable laterally thereon, a series of pluri-part disks, part of said series of pluri-part disks provided with serrated peripheries and part of said series of pluri-part 5 disks provided with draw-roll peripheries, said first-named part of said series and said last-named part of said series being interchangeable on said spiders, and means for releasably securing said respective pluri-part 10 disks to said respective spiders.

7. In a sheet delivery mechanism of the character described, the combination of a rotary transferrer comprising draw-rolls, coacting draw-rolls, a sheet-receiving device 15 having reciprocating movement under said draw-rolls, said draw-rolls acting to draw the sheet from said sheet-transferrer, and endless cords received about said rotary transferrer and comprising stretchies tangent to said draw-rolls and adjacent to said sheet-receiving device.

8. In a sheet delivery mechanism of the character described, the combination of a rotary sheet-transferrer comprising a draw-roll, a coacting draw-roll therefor, said draw-rolls acting to draw the sheet from said sheet-transferrer, and means for locating said coacting draw-roll with relation to said first-named draw-roll comprising a 25 lever in which said coacting draw-roll is mounted, adjusting means acting on said lever for forming a positive stop limiting recession of said coacting draw-roll from said first-named draw-roll, and a spring 30 urging said coacting draw-roll away from said first-named draw-roll.

9. In a sheet delivery mechanism of the character described, the combination of a rotary transferrer comprising a draw-roll, a coacting draw-roll, said draw-rolls acting 40 to draw the sheet from said rotary trans- ferrer, a shaft on which the latter is mounted, a lever in which said shaft is sup- ported, an adjustable stop acting on said lever forming a positive stop for limiting 45 recession of said coacting draw-roll from said first-named draw-roll, and a spring act- ing on said lever urging said coacting draw- roll away from said first-named draw-roll.

10. In sheet delivery mechanism of the 50 character described, a rotary sheet trans- ferrer comprising a shaft, a spider adjust- able laterally thereon, and a series of pluri- part disks respectively having different 55 sheet-contacting peripheries, the parts of said pluri-part disks respectively having parallel slots open-ended at their inner ends and securing means for said disk-parts on said spider received through said open- ended slots into said spider, whereby to re- move said disk-parts from and to replace 60 said disk-parts on said spider by movements of said disk-parts in directions at right angles to said shaft.

In testimony whereof I have hereunto 65 signed my name in the presence of two sub- scribing witnesses.

FREDERICK H. BEROLD.
